[57] CLAIM

The ornamental design for a multiple desk and cabinet tower unit, as shown and described.

DESCRIPTION

FIG. 1 is a front perspective view of the multiple desk and cabinet tower unit embodying my design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a front perspective view of an alternate embodiment of the multiple desk and tower cabinet unit shown in FIG. 1; the opposite side of the center desk being a mirror image thereof, and the opposite side of the tower cabinet being identical thereto; and,

FIG. 9 is a rear perspective view thereof.
